UNITED STATES PATENT OFFICE.

WALDO P. ADAMS, OF SYRACUSE, NEW YORK.

APPARATUS FOR PROJECTING RADIANT ENERGY.

1,190,071.

Specification of Letters Patent.

Patented July 4, 1916.

Application filed November 16, 1914. Serial No. 872,403.

To all whom it may concern:

Be it known that I, WALDO P. ADAMS, a citizen of the United States, and resident of Syracuse, in the county of Onondaga, in the State of New York, have invented new and useful Improvements in Apparatus for Projecting Radiant Energy, of which the following, taken in connection with the accompanying drawings, is a full, clear, and exact description.

This invention relates to the projection of radiant energy emanating from the incandescent filament of an electric lamp and refers more particularly to means for utilizing the energy of certain "invisible radiations" that are not transmissible through ordinary glass. In other words, the function of my invention is to utilize the radiant energy of light, emanating from an incandescent electric lamp having its incandescent filament in and uniformly around the axis and adjacent to the focus of powerful reflecting media, with the lamp bulb or envelop capable of transmitting therethrough certain "invisible" radiations of high frequency and short wave length so that the resultant radiant energy can be used in photography, printing and allied arts and also in therapeutical and pathological work.

In the drawings, Figure 1 represents, diagrammatically, one form of apparatus for carrying out the object stated. Fig. 2 is an enlarged diagrammatic view of one form of lamp filament.

In this instance, the source of light —1— is centered in the axis and focus of the reflector and is inclosed within a hollow bulb or tube —2— of rock crystal, quartz or other substance capable of transmitting therethrough definitive "blue," "violet" and "ultra-violet" radiations. The source of light is arranged in and uniformly around the focal axis of a reflector —3— which is of such size and form as to reflect and concentrate the radiations within and upon a lens or screen —4— of relatively small area and located in the focal axis of the reflector preferably between the focal point and source of light, said lens or screen being also made of rock

crystal, quartz or other substance capable of transmitting therethrough radiations of high frequency and short wave length. The lens or screen —4— is supported in a suitable frame, or housing —5— of metal or other suitable material which is preferably secured to and incloses the open end of the

reflector. In some uses, the lens or screen —4— may be omitted and the reflector made to reflect the totally reflected rays within any limited field area, and, therefore, I do not limit myself to the use of a lens nor to any particular form of reflector. When a lens or screen is used, it may be colored or clouded in such manner as to filter out certain radiations such as those of low frequencies and long wave lengths.

The term "invisible radiations" is used in its technical sense as indicating those rays which do not produce the effect of vision upon the eye, as distinguished from the "visible" or "luminous" rays, and while it may be true that quartz is the only substance known at present to be capable of transmitting therethrough the "invisible radiations" of higher frequency than the violet rays, such for example as ultra violet radiations, it is not to be assumed that other substances may not be discovered to perform the same functions as quartz, and it is for this reason that applicant does not wish to limit the present invention to the use of quartz as an inclosing medium for the incandescent filament. On the other hand, it may be possible to use rock salt as an inclosing medium for the incandescent filament in transmitting the radiations of lower frequency than red rays, such for example as infra red, and, therefore, the invention is not limited to the use of any particular material for the inclosing medium so long as it is capable of transmitting therethrough any of these invisible rays. Furthermore, as will be obvious from the foregoing description, this particular lamp may be used for projecting or transmitting "invisible" rays with or without the visible rays and independently of the reflector if desired without departing from the spirit of this invention.

The term "fixate nucleate light" is used throughout the specification and claims to briefly define an electrically incandescent filament capable of producing a highly concentrated source or nucleus of light at or near the fixed focal point of a reflector.

What I claim is:

1. In an apparatus of the character described, the combination of a fixate nucleate light, and an inclosing medium therefor including a material that will permit the passage of "invisible" radiations therethrough.

2. In an apparatus of the character described, the combination of an electrically

- incandescent filament and an inclosing medium therefor including a material that will permit the passage of "invisible" radiations therethrough.
3. In light-projecting apparatus, the combination of a metallic reflector, and an incandescent electric lamp producing a fixate nucleate of light of high intensity in and uniformly around the focal axis of the reflector adjacent the focus thereof, said light having an enveloping medium capable of transmitting therethrough certain "invisible" radiations of such light.
4. In an apparatus of the character described, the combination of a reflector, a fixate nucleate light at or immediately adjacent the focal point of the reflector, and an inclosing medium for said light including a material that will permit the passage of "invisible" radiations therethrough.
5. In light-projecting apparatus, the combination of a converging metallic reflector, and an incandescent electric lamp producing a fixate nucleate of light of high intensity in and uniformly around the focal axis of the reflector adjacent the focus thereof, said lamp having a light-enveloping medium capable of transmitting therethrough the visible and certain invisible radiations.
6. In an apparatus of the character described, the combination with a concentrating reflector, of an electrically incandescent filament located at or immediately adjacent the focal point of the reflector, and an inclosing medium for said filament including a material that will permit the passage of "invisible" radiations therethrough.
7. In light-projecting apparatus, the combination of a metallic reflector, a lens co-
- axial therewith and in the path of the reflected rays, and an incandescent electric lamp producing a fixate nucleate light of high intensity in and uniformly around the focal axis of the reflector adjacent the focus thereof, said lamp having a light-enveloping medium capable of transmitting therethrough radiations of both higher frequency and "violet" radiations.
8. In an apparatus of the character described, the combination of a metallic reflector, a fixate nucleate light of high intensity in and uniformly around the focal axis of the reflector adjacent the focus thereof, and a light-inclosing medium capable of transmitting therethrough "invisible" radiations of such light.
9. In light-projecting apparatus, the combination of a converging metallic reflector, a lens co-axial therewith and near the focus of the reflected rays, and an incandescent electric lamp producing a fixate nucleate light of high intensity in and uniformly around the focal axis of the reflector adjacent the focus thereof, said lamp having a light-enveloping medium capable of transmitting therethrough certain "invisible" radiations of such light.
10. In light-projecting apparatus, means for concentrating and projecting by reflection the visible and invisible radiations emanating from a nucleate of an incandescent electric light.

In witness whereof I have hereunto set my hand this 11th day of November 1914.

WALDO P. ADAMS.
